Int. Cl. D2—07

U.S. Cl. D2—422

FIG. 1 is a front perspective view showing my design of a cuff link.

FIG. 2 is a top plan view of FIG. 1.

FIG. 3 is a bottom plan view of FIG. 1.

FIG. 4 is a side elevational view taken from the right-hand side of FIG. 2.

FIG. 5 is a side elevational view taken from the left-hand side of FIG. 2.

FIG. 6 is a rear elevational view.

FIG. 7 is a front perspective view showing another embodiment of the cuff link design of the present invention, the top, bottom, right and left side, and rear views of the embodiment of FIG. 7 all being identical to those of the embodiment of FIG. 1.

I claim:

The ornamental design for a cuff link, as shown and described.
